METALLIC WINDOWPANE SEAL

Roy L. Eheler, Shelby, Mont., assignor of one-fifth to Malcolm P. Lyon, Shelby, Mont.

Application February 18, 1935, Serial No. 6,377

2 Claims. (CL. 20—56.4)

The present invention relates to an improvement in metallic window pane seals capable of being easily and quickly applied to the window sash to effectively secure the pane in position without the use of putty or the like.

One of the important objects of the present invention is to provide a device of this character which includes a metallic fastening strip and a non-metallic sealing strip, both of which may be formed from sheet material and bent to a predetermined shape and the fastening strip provided with prongs for imbedding in the window sash whereby to secure the pane in position, the non-metallic strip constituting a seal which is interposed between the fastening strip and the pane.

A further important object is to provide an article of this character which includes a flange on the fastening strip positioned below the upper edge thereof to provide a surface upon which pressure may be exerted by the fingers or a tool for forcing the prongs of the fastener into the sash without danger of injury to the glass should the tool slip.

Other objects and advantages reside in the special details of construction as more fully hereinafter described and claimed, reference being had to the accompanying drawing forming part hereof, wherein like numerals refer to like parts throughout, and in which

Figure 1 is a fragmentary view of a window sash with the combined fastener and seal in position thereon.

Figure 2 is a transverse sectional view of the sash.

Figure 3 is a plan view of a portion of the blank from which the fastening member is formed.

Figure 4 is a similar view of the sealing strip, and

Figures 5 and 6 are end elevational views of the fastener and sealing strip, respectively.

Referring now to the drawing in detail, wherein for the purpose of illustration I have disclosed a preferred embodiment of the invention, the numeral 5 designates the fastening member which is formed of a strip of thin metal and is bent along the dotted lines 6 into a substantially U-shaped formation, as shown in Figures 3 and 5, and also bent along the dotted lines shown at 7 to provide an angular flange 8. Each edge of the strip is provided with prongs 9 and 10, respectively.

A sealing strip 11 is also provided and preferably formed from paper or other non-metallic substance and treated with a coating of linseed oil

and white lead to make the same impervious to water. The sealing strip is likewise folded along the dotted lines shown at 12 into a substantially U-shaped formation in cross-section, as shown in Figures 2 and 6 of the drawing.

In assembling the fastening and sealing strips for placing in use, one edge of the sealing strip 11 is inserted in the channel of the U-shaped portion of the fastening strip in an interfitting relation, and as clearly shown in Figure 2 the U-shaped portion of the fastening member is inverted with the flange 8 extending outwardly and one side of the sealing strip bearing against the pane 13. Slits 14 are formed at spaced intervals in the sealing strip 11 to accommodate the prongs 9. Pressure may then be placed upon the surface of the flange 8 by a tool in a manner to force the prongs into the window sash 15.

As shown in Figure 1 of the drawing the abutting ends of the fastening strips are preferably mitered as shown at 16 to insure a neat and workmanlike finish.

It will be observed that the inner bent section 17 of the metallic strip 5, that is the portion that is nearest the glass when placed in position, is of a slightly less width than the outer bent section 18, the edge of the inner section terminating at a point designated at 19 in Figure 5. This construction creates a tendency for the metallic strip to lean inwardly in a direction to tightly force the packing strip against the pane when pressure is placed upon the device at a point adjacent the intersection of the flange 8 and section 18 or upon the rounded edge connecting the sections 17 and 18 in the usual manner for securing the pane in the sash. A tight, weather-proof seal is thus assured.

I claim:

1. A combined window pane seal and fastener comprising a metallic fastening strip and a non-metallic sealing strip bent upon themselves into U-shaped formation in cross-section, said strips being oppositely arranged with one edge of the sealing strip fitted within the channel of the fastening strip and a double row of prongs formed on the fastening strip for imbedding in the sash of the window frame, one row of said prongs being inserted through the sealing strip for securing one side thereof against the window pane, the edge of the fastening strip nearest the window being relatively short to cause the strip at a point adjacent said short edge to lean in a direction toward the pane when pressure is applied to the strip in a manner to imbed the prongs in the sash.

2. A window pane fastener comprising a metallic fastening strip bent upon itself to form a plurality of substantially parallel members, prongs on said members for imbedding in a window sash and one of said members having its edge 5 terminating short of the other and positioned

adjacent the window pane to be urged in a direction toward the pane when pressure is applied to the fastener at a point adjacent the short edge in a manner for imbedding the prongs in the sash.

ROY L. EHELER.
